Primary Examiner — Patricia A Palasik

(74) Attorney, Agent, or Firm — Nicholas J. Landau;
Bradley Arant Boult Cummings LLP(57) **CLAIM**

The ornamental design for a robot, as shown and described.

DESCRIPTION

FIG. 1 shows a perspective view the robot in accordance with the new design.

FIG. 2 shows a rear view of FIG. 1.

FIG. 3 shows a front view of FIG. 1.

FIG. 4 shows a first side view of FIG. 1.

FIG. 5 shows a second side view of FIG. 1.

FIG. 6 shows a top view of FIG. 1; and,

FIG. 7 shows a bottom view of FIG. 1.

Dashed lines in the drawings depict portions of the robot which form no part of the claimed design.

1 Claim, 7 Drawing Sheets(56)
